2 Claims. (Cl. 250—175)

This invention is related to an amplifier utilizing secondary emission with several cascaded stages of amplification. In these amplifiers a beam of electrons impacts an emitting electrode with such velocity that the ratio of secondary electrons to primary electrons is greater than unity. The secondary electrons are again accelerated and the process of secondary electron amplification is repeated in further amplification stages. 5 The anode of each amplifier stage represents the cathode of the following stage.

In amplifier tubes of this type, as known so far, the disadvantage existed that the accelerating fields in the different amplification stages 10 were not clearly separated. Of the lines of force which ended on every emitting electrode, some had the tendency to accelerate the electrons towards the electrode, whereas others had the tendency to draw the electrons away from this electrode. As a consequence thereof, many electrons passed the emitting electrode without impacting, and thereby did not contribute to the amplification by generation of secondaries. Furthermore, the generation of a space charge was here- 15 by favored. These phenomena impaired the efficiency of the amplifier. According to the invention, the accelerating fields between two subsequent amplification stages are separated by a permeable auxiliary electrode disposed between 20 two consecutive emitting electrodes. The auxiliary electrode is held at about the same potential as the second of the above mentioned emitting electrodes. Preferably, a grid structure is used as an auxiliary electrode and is directly connected with the following emitting electrode. The auxiliary electrode may also consist of a foil, or a sieve, or a combination of these elements. The lines of force of the electric field in one stage run from the foregoing electrode to the grid, so 25 that the lines of force of the following amplification stage have the full area of the next emitting electrode at their disposal. The electrons are accelerated by the grid to a velocity suitable to liberate secondaries and fly with this velocity 30 through the grid toward the emitting electrode. With a suitable construction of the emitting and auxiliary electrodes, the influence of the field of the following amplification stage on the electrons is very slight because of the high velocity 35 of the latter. Thus use is made of nearly all electrons traveling through the grid for secondary emission, and all liberated secondary electrons are accelerated towards the following emitting electrode.

55 Only a small amount of electrons will strike the

grid. These electrons may be also made useful for the amplification by coating the grid with a strongly secondary emissive material as, for instance, caesium.

The further improvement of the efficiency is 5 obtained by spacing a further auxiliary electrode, preferably a grid, between the emitting electrode and the following auxiliary electrode. This further auxiliary electrode will be then held at a potential between that of the emitting electrode 10 and a first auxiliary electrode. The arrangement and the intermediate potential are preferably chosen in such a manner that the acceleration of the electrons occurs substantially in a homogeneous field between the two auxiliary 15 grids. If the potential of the further auxiliary grid (hereafter referred to as the intermediate grid) is suitably chosen, all electrons of the foregoing stage must strike the emitting electrode. At the same time the voltage is chosen in such 20 a manner that all secondary electrons are drawn away from the emitting electrode by the intermediate grid. Usually the voltage between the intermediate grid and the emitting electrode will 25 be a fraction of the total of the acceleration voltage.

Figure 1 shows a cross-section of an amplifier utilizing secondary emission of the known kind.

Figures 2, 3 and 4 show modifications of amplifiers with auxiliary electrodes, according to the 30 invention.

In Figure 1, 1, 2, 3, 4, 5 and 6 are emitting electrodes disposed in the interior of a highly evacuated amplifier tube 15. The potential difference between subsequent electrodes is constant, for instance, if the potential of the second electrode is 400 volts in respect to that of the first electrode, every following electrode will be 400 volts higher than the foregoing electrode. Electrons are liberated on the cathode 1, for instance, by photo-emission, and are first accelerated towards the electrode 2, where they liberate secondaries which are accelerated toward the electrode 3. The process of secondary emission is then repeated. The same happens on the electrodes 4, 5 and 6. Further emitting electrodes may follow the electrode 6, but are not shown in the drawings. The end electrode, which is also not shown, serves as a collector.

From the course of the indicated lines of force, 50 it may be seen that lines of force of different directions end on each of the electrodes 2, 3, 4, 5 and 6. Furthermore, it may be seen that quite a few lines of force lead immediately to the electrode following the next, thus leaving one elec- 55

trode out. An electron which may, for instance, leave in the middle of an emitting electrode, will first follow the lines of force and will then travel with comparatively high velocity parallel to the electrodes without striking. Thereby, the electron is lost for the amplification by secondary emission.

Figure 2 shows how the arrangement shown in Figure 1 is provided with grids 7, 8, 9, 10 and 11 according to the invention, which grids are at the same potential as the following emitting electrodes. Again lines of force are indicated from the course of which may be seen that all lines of force of one stage now end on the inserted grid, so that the total area of the emitting electrode is penetrated by lines of force of the following acceleration stage.

Figure 3 shows another modification in which a further grid is disposed between the auxiliary electrode and the emitting electrode. Voltages, increasing in steps of 400 volts, are applied to the electrodes 2, 3, 4 and 5. Grids 8, 9 and 10 correspond to those marked by the same numbers in Figure 2. Between each of the grids 8, 9 and 10 and the foregoing electrode, further intermediate grids 12, 13 and 14 are arranged, which are held at a potential of about 50 volts above the foregoing electrode. The shaping of the electric field is schematically shown in the drawings. The acceleration of the electrons occurs substantially between the two grids. The voltage of the grids 12, 13 and 14 in respect to the electrodes 2, 3 and 4, is chosen in such a manner that no noticeable influence is exerted on electrons of high velocity flying through the grids 7, 8 and 9, but that all secondaries emitted by the plates 2, 3 and 4, which at first have only a low velocity, are accelerated towards the grids 12, 13 and 14, and thus guided to the next amplification stage.

Figure 4 shows a further modification, in which the surface of the emitting electrodes increases from stage to stage, so that the current density per unit of area stays approximately constant. In the vacuum receptacle 15 is the thermionic cathode 16, which emits the primary electrons, the number of which is controlled by the grid 17. The electrons impact a cone shaped first emitting electrode 18 and liberate secondaries which leave the cone 18 substantially perpendicular to the axis of the cone 18, and arrive at the

second emitting electrode 19. This electrode has the shape of a truncated cone, from the inner wall of which secondaries are liberated by the electrons coming from the electrode 18. These secondary electrons are accelerated towards a third emitting electrode 20, which has also the shape of a truncated cone. The procedure of secondary emission repeats itself at the electrodes 21, 22 and 23, the construction of which is similar to the electrodes 19 and 20. The numbers 10, 7, 8, 9, 10 and 11 again indicate grids which are at the same potential as the electrodes 19, 20, 21, 22 and 23 respectively. The electrons from the electrode 23 are collected by the collector 24.

I claim:

1. An electron multiplier comprising an envelope having therein electrodes, each of said electrodes having an electron emissive surface of area different from that of the other electrode surfaces, means supporting said electrodes with said emissive surfaces arranged in the order of their progressively increasing areas and positioned substantially parallel to each other to be successively impacted by an electron stream emitted by an initial one of said surfaces, the arrangement of said surfaces normally producing undesirable electrostatic fields between alternate ones of said surfaces which detrimentally affect the movement of said electron stream between successive ones of said surfaces, and electron permeable means positioned in the path of said electron stream between each pair of said surfaces at an angle with respect to the electron path between said surfaces for reducing the detrimental effects on the movement of said electron stream of said electrostatic field.

2. An electron multiplier comprising an envelope having therein a series of secondarily emissive electrodes, and means for developing electrostatic fields only between successive electrodes in such series and preventing the development of electrostatic fields between electrodes other than successive electrodes, said means comprising a plurality of electron permeable grids disposed between successive electrodes, one of said grids being directly connected to the electrode of the higher stage and the other of said grids being free for application thereto of an electromotive force slightly above that to be applied to the electrode of the lower stage.

HEINRICH STRÜBIG.
